Matthew W. Mitchell

(57) **CLAIM**

The ornamental design for a welding cuff having hook and loop attachments and a pocket, as shown and described.

DESCRIPTION

FIG. 1 is a front, top perspective view showing my new design;

FIG. 2 is a front, bottom perspective view thereof;

FIG. 3 is a rear, top perspective view thereof;

FIG. 4 is a rear, bottom perspective view thereof;

FIG. 5 is a top view thereof;

FIG. 6 is a bottom view thereof;

FIG. 7 is a front view thereof;

FIG. 8 is a rear view thereof;

FIG. 9 is a right-side view thereof; and,

FIG. 10 is a left-side view thereof.

The broken lines shown around the perimeter of the welding cuff and pocket represent stitching and form part of the claimed design.

1 Claim, 10 Drawing Sheets
